F. ZUNINO

RATTAN FERN BOX

Filed May 3, 1923

INVENTOR

FERDINANDO ZUNINO

BY Arthur H. Sles.
ATTY.

UNITED STATES PATENT OFFICE.

FERDINANDO ZUNINO, OF SAN FRANCISCO, CALIFORNIA.

DESIGN FOR A RATTAN FERN BOX.

Application filed May 3, 1923. Serial No. 6,051. Term of patent 3½ years.

To all whom it may concern:

Be it known that I, FERDINANDO ZUNINO, a citizen of the United States, residing in the city and county of San Francisco and State of California, have invented a new, original, and ornamental Design for a Rattan Fern Box, of which the following is a specification, reference being had to accompanying drawing, forming part thereof.

The figure is a perspective view of a rattan fern box showing my new design.

I claim:

The ornamental design for a rattan fern box as shown.

FERDINANDO ZUNINO.
